UNITED STATES PATENT OFFICE.

OMER C. BARGER, OF INDIANAPOLIS, INDIANA.

INSULATOR.

1,304,247.

Specification of Letters Patent.

Patented May 20, 1919.

Application filed June 24, 1918. Serial No. 241,628.

To all whom it may concern:

Be it known that I, OMER C. BARGER, a citizen of the United States, and a resident of Indianapolis, county of Marion, and State of Indiana, have invented a certain new and useful Insulator; and I do hereby declare that the following is a full, clear, and exact description thereof, reference being had to the accompanying drawings, in which like numerals refer to like parts.

This invention relates to improvements in insulators, and more particularly to that class adapted to be used for carrying currents of very high voltage, and the prime feature of the invention is the provision of an insulator, preferably formed of glass, having a shield, the under face of which is provided with a series of convolutions whereby an extended surface is provided to prevent creepage of the current over the outer surface of the glass portion of the insulator.

A further feature of the invention is the provision of extensions above and below the shield and axial therewith, said extensions having radial ribs at their free ends. A further feature of the invention is the provision of hangers for engagement with the extensions, said hangers being preferably formed in sections and bolted in engagement with the extensions.

A further feature of the invention is the provision of ears on the hangers, the ears of one hanger being placed face to face against each other so as to form a tongue which is designed to be entered between the ears of the other hanger which are placed in separated position, so that any number of insulators may be secured together.

A further feature of the invention is the provision of cushioning means between parts of the hangers and parts of the extensions which not only protect the extensions against casual breakage, but also compensate for contraction and expansion between the metal and glass parts without danger of injury or breakage of the glass parts.

The full nature of the invention will be understood from the accompanying drawings and the following description and claims:—

In the drawings, Figure 1 is a side elevation of the insulator and the hangers therefor. Fig. 2 is a sectional view thereof as seen on line 2—2 of Fig. 1. Fig. 3 is a sectional view through a part of one of the

hangers, and Fig. 4 is a side elevation showing a number of the hangers secured together.

Referring to the drawings in which similar reference numerals designate corresponding parts throughout the several views, 1 indicates the insulator proper, which comprises a shield or apron 2, and extensions 3 and 4, above and below the shield 2 respectively, the free ends of the extensions 3 and 4 having peripheral ribs 5 and 6 respectively.

In order to suspend the insulator 1, which is preferably formed of glass, although it may be made of any preferred substance, hangers 7 and 8 are secured respectively to the extensions 3 and 4, each hanger comprising a pair of semicircular sleeves 9, each having a base section 10 at one end and an inwardly extending flange 11 at the opposite end, the base portion 10 of the hangers resting upon the ends of the extensions of the insulator, while the flanges 11 extend over the ribs of said extensions and when the sections of the hangers are secured together the hangers will be securely locked in engagement with the insulator.

The two sections of the hangers are secured together and locked in engagement with the extensions by inserting bolts 12 through openings 13 in the base sections 10, said bolts having nuts 14 threaded thereon to clamp the sections of the hangers together, the nuts being held against reverse rotation by means of cotter pins 15 or in any suitable manner and when the parts of the hangers are so secured together and the nuts are locked on to the bolts, it is impossible for the nuts to become loosened by vibration.

The corners of the ribs 5 and 6 are rounded as indicated at 16 and extending over the edges of the ribs are strips of cushioning substance 17, preferably of lead, said strips of cushioning material entirely covering the peripheral edges of the ribs, and one edge of each cushioning strip rests over the face of the ends of the extension for a distance, while the opposite edges of said strips are extended parallel with the extensions 3 and 4, and the ends of the flanges 11. The object in providing the cushioning material is to protect the glass portion of the insulator against becoming broken from strain or otherwise, and also to compensate for the expansion or contraction for any uneven-

ness that might occur on the inner surface of the hangers which, if brought into direct contact with the glass portion of the insulator, would possibly break or crack the same.

5 The sections of the hanger 7 are each provided with an ear 18 which ears are spaced from the meeting edges of the sections while the sections of the hanger 8 are each provided with an ear 19 which are positioned at the meeting edges of the sections of the hanger 8, so that they will rest against each other when the sections of the hanger are secured to the insulator, the ears 19 being adapted to extend between the ears 18 of the next adjacent hanger, and by extending a pin 20 through the ears 18 and the interposed ears 19, a plurality of insulators may be secured together.

10 To more securely guard against the current passing over the surface of the shield 2, so as to form a circuit between the hangers 7 and 8, the under face of the shield 2 is provided with a plurality of depending concentric ribs 21 which are of considerable depth, thereby creating an unusually extended surface over which the current would have to travel before passing from one hanger to the other. By providing the hangers in sections, they can more readily be attached to or removed from the glass portion of the insulator, and by providing the sheets of cushioning substance, between the hangers and the glass portion of the insulator, all possibility of breaking or in any manner injuring the glass insulator is obviated, and likewise the cushioning material will permit the contraction or expansion of the parts of the insulator without danger of injury to the glass portion thereof.

15 20 25 30 35 40 It will likewise be seen that this device can be very cheaply constructed and quickly as-

sembled together and that a battery of the insulators may be quickly assembled and applied to use.

It will likewise be seen that by forming 45 the extensions of considerable length beyond the shield portion of the insulator, and by providing a plurality of concentric ribs on the lower face of the shield, all possibility of the current passing around the glass portion of the insulator from one hanger to another is entirely obviated.

The invention claimed is:—

An insulator construction, including a shield, extensions on each side of the shield, 55 a rib at the outer end of each extension, hangers formed of a pair of substantially semi-cup shaped members, an inwardly extending flange at the open ends of said members adapted to engage said ribs, a bolt extending transversely through each pair of hanger members beyond the ends of said extensions for engaging the hangers with the ribs of the extensions, an ear on each hanger section extending flatwise to the straight edge of the section, the ears of one pair of hanger sections being in line with the meeting edges of the sections so as to form a single element, and the ears on the section of the companion hanger being flatwise to 70 the meeting edges of the sections and placed a distance apart to receive the ears forming the single element, and means for pivotally securing the ears of one hanger to the ears 75 of the next succeeding hanger.

In witness whereof, I have hereunto affixed my signature in the presence of the witnesses herein named.

OMER C. BARGER.
